BUILDING

Clarence S. Shank, 145 N. Market St., Wooster, Ohio, assignor of one-half to Robert Critchfield, Wooster,
Ohio

Filed June 21, 1963, Ser. No. 75,466
Term of patent 14 years

(Cl. D13—1)

FIG. 1

FIGURE 1 is a perspective view of a building embodying my new design which is especially suited for use as a restaurant;

The dominant features of the design reside in the portion shown in full lines. The side of the building not shown is substantially the same as the side shown in FIGURE 3 and the rear, not shown, is substantially plain.

I claim:

The ornamental design for a building, as shown and described.
